[57] CLAIM

The ornamental design for a combined cup and token or the like, as shown and described.

DESCRIPTION

FIG. 1 is a bottom perspective view of a combined cup and token or the like showing my new design;

FIG. 2 is a bottom plan view;

FIG. 3 is a side elevational view on a reduced scale.
The characteristic features of my design reside in the appearance and configuration of the bottom of the combined cup and token or the like.
